Application October 15, 1954, Serial No. 462,487

3 Claims. (Cl. 135—25)

This invention relates to umbrellas of the folding type, and has for its object to provide an improved form thereof.

The present invention consists of a collapsible umbrella frame comprising an inner rib part, an outer rib part pivoted thereto at a point inwardly spaced from the end of the outer rib, a stretcher and a coupling member pivoted to said outer rib part and to said stretcher, and means for limiting the angular pivotal movement of said coupling member with respect to said outer rib part.

Other features and advantages will appear from the following description of one embodiment thereof, in conjunction with the accompanying drawings in which

Figure 1 is a fragmentary view of an umbrella frame showing one rib in the extended position,

Figure 2 is a detail of the rib structure of the frame of Figure 1, to an enlarged scale, and

Figure 3 is a further detail, similar to Figure 2 but showing the parts in the position they assume when the frame is collapsed.

The umbrella frame includes a stick 10, which may in known manner be collapsible or telescopic, or made in two readily separable parts. On the stick is a conventional slide 11 which can be retained by catch 12, and a crown 13. The ribs, of which one is shown, each have an inner part 14 and an outer part 15; these are pivoted together by means of a member 16 at a point spaced inwardly from the end of rib part 15. The stretchers 17 are each connected to the related rib by a coupling member 18, more clearly shown in Figures 2 and 3.

The coupling member 18 is pivoted to the outer rib so that the pivotal movement is limited in both directions. With this object the coupling member is pivoted to the outer rib at a point 19 inwards from the end of the latter, and the member is made with two spaced side pieces, between which the outer rib passes and joined by a part 18a. The movement of the coupling member with respect to the rib is limited by the top edge of the rib, as it appears in Figure 2, striking one edge or the other of the part 18a. The end of the stretcher passes between the two sides of the coupling member 18 and is pivoted to it at 20.

The umbrella frame operates in the following way. Starting from the approximately normal position shown in Figure 1, the catch is released, and the slide moved downwardly. The umbrella then closes in the manner of a conventional umbrella, and it is possible to continue the folding until the umbrella is folded, as in the usual way. In the folded position the stretcher lies substantially parallel to the outer rib part, as indicated by the chain line in Figure 2. When so folded the coupling member 18 will be seen to have pivoted to one limit of its movement with respect to the two parts 14 and 15 of the rib; it is therefore arranged that this movement is limited to the extent necessary to enable parts 15 and 17 to be brought parallel to each other.

It is also to be observed that if the umbrella is opened from the folded position, as the full open position is reached the corner 18b of the coupling member 18 will, if the coupling is not in line with the outer rib part 15,

2

strike the inside edge of the part 14, and thus tend to turn the coupling member into the desired position in line. A resilient ring 21 can be used on the stick to assist the initial movement of the inner rib parts when opening the umbrella from the folded position.

To collapse the umbrella, it is turned to the folded position as described above, and the outer rib parts are pivoted outwardly and upwardly, until they lie next to the inner rib parts in the relative positions shown in Figure 3, and then the slide is moved upwardly as far as it will go, when the stretcher and the rib parts are all as shown in Figure 3.

In this collapsed position the coupling member assumes the other limit of its movement with respect to the outer rib, this movement being just sufficient for the purpose.

With the construction described there is provided an umbrella which can be easily collapsed or folded and which can be made with parts which, but for the coupling member 18 which is a small and simple part, are of conventional construction and readily available.

We claim:

1. A collapsible umbrella frame comprising a handle stick, a runner on said stick, a plurality of ribs pivoted on one end of said stick, a plurality of stretchers one between said runner and each of said ribs, each stretcher being pivoted at one end to said runner, each of said ribs comprising an inner rib part and an outer rib part pivoted together at a point outwardly spaced from the inner end of the outer rib part, and a plurality of coupling members each pivoted to an outer rib part at a second point spaced from but nearer the inner end of the respective outer rib part than the first point and to the other end of the respective stretcher, each of said coupling members abutting one side of the respective outer rib part to limit rotation of the coupling member about its pivot in one direction relative to the said outer rib part and each of said coupling members also abutting said one side of the respective outer rib part to limit a rotation in the opposite direction.

2. A collapsible umbrella frame comprising a handle stick, a runner on said stick, a plurality of ribs pivoted on one end of said stick, a plurality of stretchers one between said runner and each of said ribs, each stretcher being pivoted at one end to said runner, each of said ribs comprising an inner rib part and an outer rib part pivoted together at a point outwardly spaced from the inner end of the outer rib part, and a plurality of coupling members each pivoted to an outer rib part at a second point spaced from but nearer the inner end of the respective outer rib part than the first point and to the other end of the respective stretcher, each of said coupling members having two parallel side members between which the respective end of the outer rib passes and an integral part joining the side members near one end thereof, rotation of said coupling member about its pivot relative to the respective outer rib part being limited in both directions by said integral part abutting said outer rib part.

3. A collapsible umbrella frame comprising a handle stick, a runner on said stick, a plurality of ribs pivoted on one end of said stick, a plurality of stretchers one between said runner and each of said ribs, each stretcher being pivoted at one end to said runner, each of said ribs comprising an inner rib part and an outer rib part pivoted together at a point outwardly spaced from the inner end of the outer rib part, and a plurality of coupling members each pivoted to an outer rib part at a second point spaced from but nearer the inner end of the respective outer rib part than the first point and to the other end of the respective stretcher, whereby said umbrella frame is collapsible to respectively a position where the inner rib part lies between and approximately parallel to the stretcher and the outer rib part and a folded position where the stretcher lies against and approximately parallel to the outer rib

part, said coupling member comprising two parallel side members between which the end of the outer rib passes and an integral part joining the ends of the side members, rotation of said coupling member about its pivot relative to said outer rib part being limited in either direction by said integral part abutting one side of said outer rib part. 5
